UNITED STATES PATENT OFFICE.

CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND.

EXPANSIBLE BAND OR BRACELET.

Application filed July 27, 1926. Serial No. 125,233.

This invention relates to improvements in expandable metal bands, chains, or linkages for use as articles of jewelry such as bracelets, necklaces, girdles and the like.

5 A principal object of the invention is to provide an improved article of manufacture of the type specified comprising articulated links or chain-elements which are adapted to flex, one in relation to another, and to slide longitudinally relatively to each other to 10 allow expansion in the length of the bracelet or other article.

Another object of the invention is to provide an expandible band, chain, or linkage in 15 which the individual links may be easily disconnected and detached to shorten the length of the bracelet or other article and to permit the insertion of added links to lengthen the bracelet.

20 Another object of the invention is to provide an article of the type specified in which the links may be constructed from sheet metal blanks struck up in dies and assembled in interconnected relation without the use of 25 pins, rivets, or soldered joints.

Another object of the invention is to provide an article of the type specified having a neater and more ornamental appearance, and of stronger construction and proof against 30 breakage or damage in use.

Further objects of the improvement are set forth in the following specification which describes a preferred embodiment of the invention as illustrated by the accompanying 35 drawings. In the drawings:

Fig. 1 is a perspective view illustrating the general appearance of the band or chain and showing it with its links in contracted relation, but flexed in substantially circular form;

40 Fig. 2 is an enlarged bottom plan view showing several of the connected links and illustrating a portion thereof in section to disclose the resilient expansion-means enclosed therein;

Fig. 3 is a side view of several of the links showing two of the main links in section on the line 3—3 of Fig. 2;

45 Fig. 4 is a cross-sectional view of one of the links taken on line 4—4 of Fig. 2 and showing the arrangement of the expansion-springs which are held within the outer main links;

Fig. 5 is a perspective view showing the 50 under side of two sections of the assembled

links and illustrating the manner in which the inner sliding-link is drawn out to be hooked into connection with the next adjacent main link;

Fig. 6 is a perspective view of the outer or 55 main link showing its end-bar removed;

Fig. 7 is a perspective view showing the two elements of the inner sliding-link; and

Fig. 8 is a perspective view showing the construction of the central link which may 60 be used to fasten the two sections of the bracelet together.

My improved band, chain or linkage consists in general of a series of main elements or outer link members 2 of substantially box-like form assembled with inner connecting-links or slides 3 which are telescoped within the main links and held in contracted relation by resilient means such as the springs 4 to adapt them to be drawn out or extended 65 in relation to the main links to provide for the expansion of the band or chain as a whole. The main links 2 are open at the center along their under sides and the inner sliding connecting-links are provided with hooks at their 70 ends for engaging with the end cross-bars of the main links. The inner links also have portions extending between the open sides of the main links and engaging beneath the hooks in the manner of a latch or keeper to 75 hold the links in connected relation. One novel and essential feature of the present invention consists in constructing the latch or keeper as a separate piece from the inner sliding-link and adapting it to be maintained 80 in closed relation with respect to the hook on the slide by means of the inner expansion springs whose main purpose is to hold the 85 links in contracted or closed relation.

Fig. 1 illustrates the general appearance of 90 a bracelet embodying the improved construction of the links and provided with clasps at its ends for attaching it to the bails of a wrist watch or other article of jewelry.

As shown more particularly in Figs. 2 and 95 6, the outer or main links 2 are constructed from sheet-metal blanks having a main flat portion which forms the top 5 or exposed portion of the link and sides 6 folded at right-angles thereto. The sides 6 are folded over 100 again on the bottom of the link to form longitudinal strips or flanges 7 extending parallel with the top of the link. At one end of the main link 2 the stock is punched with a lateral slit 8 and bent at right-angles to the 110

top of the link to provide a cross-bar 10. The cross-bar 10 is bent or bowed outwardly from the end of the link 2 to provide for the entrance of the hook on the adjacent link 5 through the slit 8 to adapt it to hook around the bar in the manner as hereinafter more fully explained. The ends of the cross-bar 10 are joined to the top portion 5 of the link by portions 11 which are folded within the sides 6 and held in position by tabs or ears 12 bent over from the ends of the longitudinal side-strips or flanges 7. The side-strips or flanges 7 also have tabs 13 bent over at their opposite ends and adapted to engage the ends of a 15 second loose cross-bar 15 which projects across the open end of the main link 2. The cross-bar 15 is crimped or folded at its center to provide a projecting prong 16 which serves as a separator and steadyng means for the 20 pair of springs 4, see Fig. 2, enclosed within the link 2 to act on its slide 3.

The inner connecting-link or expansion-slide 3 is constructed in two parts as illustrated in perspective view in Fig. 7. The 25 main slide 3 consists of a relatively flat strip or plate of sheet-metal having a narrowed tab or extension 18 bent or curled over at its end to form the hook 20. At the opposite end of the slide 3 the stock is folded up to form a 30 right-angled strip 21 having the central portion of its edge slightly crowned or raised with respect to the ends thereof. The end portions of the strip 21 are of such width as to adapt them to be received within the 35 confines of the space between the longitudinal bottom strips or flanges 7 and the top 5 of the main link 2 when the slide 3 is inserted therein with its main portion abutting the bottom of the top plate 5; it being understood that in the present drawings the detailed views of the links show them in inverted 40 position to more clearly illustrate their form and construction.

As before stated, the latch or keeper-member 25 of the slide-link 3 is made separate therefrom and comprises a flat strip of sheet-metal folded over at one end in a cross-strip 26. The cross-strip 26 is adapted to abut and overlie the side of the end-strip 21 of the 50 slide-link 3 with its end portions 27 held between the flanges 7 and the flat top of the slide in the manner as shown most clearly in Fig. 2. The main portion of the latch 25 will thus be held in place extending between 55 the inner longitudinal edges of the side strips or flanges 7 of the link 2 with its forward end engaged under the beak of the hook 20 on the slide 3, see Fig. 5. The end portions 27 of the strip 26 of the latch 25 are punched or 60 sheared to provide thin strips or prongs 28 which project forwardly therefrom in position to engage within the end coils of the springs 4 housed within the main link 2. As shown in Figs. 2, 3 and 4, the springs 4 are 65 flattened with their coils of substantially oval

shape to adapt them to be contained within the space between the main portion of the slide-link 3 and the latch 25. As illustrated more particularly in Fig. 2, the springs 4 extend in parallel relation between the end portion 26 of the latch 25 and the end cross-bar 15 of the outer link 2 and are held in spaced-apart relation by the prongs 28 on the member 26 and prong 16 on the cross-bar 15. It will be understood that the springs 4 act between the cross-bar 15 of the link 2 and the end portion 26 of the latch 25 which bears against the end portion 21 of the slide 3, to hold said slide retracted or telescoped within the link 2. When the slide-link 3 is drawn out to the position illustrated at the right in Fig. 2 the springs will be contracted in the manner as here shown.

The several elements of the improved band, chain or linkage are assembled in cooperative relation in the manner as next explained. The slide 3 is first inserted within the main link 2 by hooking its end 21 through the openings between the end-tabs 13 and the top-plate 5. The slide is then slid back until its end portion 21 strikes against the folded portions 11 of the cross-bar 10 on the main or outer link 2. The slide 3 is inserted within the link 2 before its hook 20 is completely formed so that the latch-member 25 may be applied to place by canting it and inserting its ears 27 under the flanges 7 of the main link 2, considering the latter in its inverted position as shown in Fig. 6. The end portion 26 of the latch 25 is pushed back into place against the end-strip 21 on the slide 3 and the springs 4 are placed thereunder with their end loops engaged by the prongs 28. It will be understood, of course, that in assembling the parts in this manner the latch 25 is free to be swung upwardly to allow for the insertion of the springs thereunder, and also that before the springs are placed in position the cross-bar 15 is applied to the main link 2 with its ends engaged with the end tabs 13 thereof. Now when the latch 25 is brought into place between the edges of the longitudinal side strips or flanges 7 the hook 20 is bent over with the edge of its beak overlapping the end of the latch to hold the latter in position to retain the other elements in place. It will thus be seen that the several interconnected parts of the link may be assembled without the use of pins, rivets, or soldered joints and with very little hand work as compared with that required in the manufacture of similar articles.

In operation, the springs 4 hold the end portion 26 of the latch 25 pressed against the end-strip 21 of the slide-link 3 and bearing at their opposite ends against the cross-bar 15 of the main link 2 they tend to maintain the link 3 telescoped within the link 2. The pressure of the springs against the end portion 26 of the latch 25 also tends to hold this

part flat against the end-strip 21 of the slide 3 so that the latch 25 is maintained in parallel relation with the main strip of the slide with its forward end resting snugly against the beak of the hook 20. Usually in assembling the links in a bracelet, particularly a wrist-watch bracelet such as shown in Fig. 1, the two end sections thereof have their links arranged in opposite relation, the clasp-members 30 at the ends of the bracelet being constructed in the same form as the main links with slides projecting from their box portions and provided with hooks to hook into the ends of the box-links to which they are connected. This requires that the two sections of the bracelet be joined at the center by a dead link 31. The central connecting or dead link 31 is preferably smaller than the other links and may be constructed in the form shown in Fig. 8. As illustrated in this view it consists of a sheet-metal blank having sides 32 folded inwardly to provide bottom flanges 33 and opposite ears or tabs 34 bent over to engage the end cross-bars 35 which are folded over from the main strip of the link.

It has been explained that the slides 3 are normally maintained telescoped within the outer main links 2, and it is to be understood that each slide 3 has its hook 20 inserted through the slit 8 and around the cross-bar 10 of the next adjacent main link of the series, see Figs. 2 and 3. To assemble the links in this relation it is simply necessary to draw the slide-link 3 out from the end of the main link 2 as shown at the right in Figs. 2 and 3. Normally, as before explained, the pressure of the springs 4 against the end-member 26 of the latch 25 holds the latter in position with its end pressing against the edge of the beak of the hook 20; but when the slide 3 is withdrawn from the end of the link 2 the latch may be rocked by pressing down on its end as indicated at the right in Fig. 3. That is to say, with the springs 4 under compression the latch 25 will be free to rock to carry its forward end away from the beak of the hook 20 so that the hook may be readily engaged with the cross-bar 10 on the next main link 2. Preferably, the latch 25 is constructed of somewhat thinner stock than the other parts of the link so that it is flexible of itself to be sprung away from the hook. This construction and arrangement of the parts of the device not only provides for convenience and facility in connecting the links in the chain, but also allows for the adjustment in the length of the bracelet or other article by the detachment of one or more links therefrom or the insertion of additional links therein.

It will be observed from the above that my invention provides a particularly simple construction for articles of the type specified, whereby the cost of manufacture is materially reduced. The elimination of pins, rivets,

screws and soldered joints reduces the amount of machine and hand labor required in manufacture and as certain of the elements are made to function for several purposes the whole number of parts of the device is considerably reduced. The improved construction of the device also makes for simpler operations in assembling the parts and interconnecting the links and the complete article is not only neater and more ornamental in appearance, but more convenient to operate in attaching and detaching the individual links. The improved band, chain, or bracelet is also less liable to wear or breakage and is stronger and more durable in use than similar articles of the same type.

While I have herein shown and described a preferred embodiment of the invention it is to be understood that various modifications may be made in the form and structure of the various component parts of the device without departing from the spirit or scope of the invention.

Therefore without limitation in this respect, I claim:

1. In an expandible band, chain, or linkage, the combination of outer box-like links having bottom flanges extending inwardly from their sides, slides slidable within the outer links and provided with hooks at their ends adapted to engage the ends of adjacent links, springs enclosed within the links and acting to maintain the slides in telescoped relation, and separate latch-members assembled on the slides and normally held in position by the springs with their ends cooperating with the open ends of the hooks to close the latter, said latch-members being adapted to be manually rocked against the action of the springs to open the hooks.

2. In an expandible band, chain, or linkage, the combination of outer box-like main links having closed sides with strips or flanges extending inwardly therefrom at the bottom, slides slidable beneath the top of the main links and having portions held between the top-portions and bottom-flanges thereof, said slides formed with hooks at one end, separate latch-members assembled on the slides with their ends engaging beneath the beak of the hooks and provided with portions abutting the opposite end-portions of the slide, and springs extending between the end-portions of the latches and the ends of the main links, said springs tending to maintain the slides telescoped within the main links while also acting against the end-portions of the latches to hold them flat against the end-portions of the slides to maintain the opposite ends of the latches bearing against the inner side of the hooks.

3. In a device of the type specified, the combination of an outer box-link formed with a relatively flat top with sides extending downwardly therefrom and lateral flanges

extending inwardly at the bottom thereof, cross-bars at the ends of said main links, a slide comprising a relatively flat plate slidable within the main link and formed with a hook 5 projecting at its end, said slide having an end-strip held between the top of the main link and its bottom flanges, a separate latch-member having an end-portion with projecting ears held between the top of the slide and the bottom flanges of the main link with said end-portion abutting the end-strip on the slide and the latch flush with the bottom flanges on the main link, and a spring arranged between the slide and the latch to 10 bear at one end against the end portion of the latch to hold it flat against the end-strip of the slide and with its opposite end bearing against the cross-bar of the main link, said spring tending to maintain the slide telescoped within the main link and its latch held in position with its end engaged with the beak of the hook.

4. In a device of the type specified, the combination of a main link formed with a relatively flat top, sides bent downwardly therefrom and folded inwardly to provide longitudinal flanges, said flanges bent upwardly at their ends, cross-bars extending between the bent ends of the side flanges, a slide-link 25 slideable beneath the top-portion of the main link and adapted to project therefrom at one side of the end cross-bar thereof, said slide-link provided with a right-angled end-strip and a hook at its opposite end projecting from the main link, a separate latch-member having a relatively flat portion arranged between the edges of the bottom flanges of the main link flush therewith and provided with an end-portion bent at right-angles and formed with 30 ears held between the top and the bottom flanges of the main link with the forward end of said latch engaged with the beak of the hook on the slide-link, and a pair of springs held between the latch and the top of the slide-link and bearing at one end against the cross-bar of the main link and at their opposite ends against the end portion of the latch to hold it flat against the end-strip of the slide in the manner and for the purpose substantially as described.

5. In a device of the type specified, the combination of a main link having a top-portion with sides bent downwardly therefrom and folded inwardly to provide side-flanges, a fixed cross-bar at one end of the

link, a removable cross-bar at the opposite end of said link, a slide slidable within the main link and provided with an end portion held between its top and bottom-flanges, said slide provided with a hook at its opposite end, a separate latch-member having an end-strip overlying and abutting the end portion of the slide and held in place between the top of the main link and its bottom-flanges with its end engaging under the edge of the hook on the slide, and a spring held between the latch and the slide with one end bearing against the end-strip of the latch to hold it flat against the end-portion of the slide and the opposite end held by the removable cross-bar on the main link.

6. In a device of the type specified, the combination of a main link having a top with sides bent downwardly therefrom and folded inwardly to provide lateral bottom-flanges, 60 tabs bent over from the ends of the bottom-flanges, said link having a slotted end portion bent downwardly and held by the tabs on the bottom-flanges folded thereover, a removable cross-bar extending between tabs bent over from the opposite ends of the bottom-flanges, a slide slidable within the main link and provided with an end-strip held between the top and bottom-flanges thereof, said slide 65 also provided with a hook at its opposite end, a latch having an end-strip overlying and abutting the end-strip on the slide and provided with forwardly projecting prongs, said latch arranged with its free end engaged with the beak of the hook, and a pair of springs arranged between the slide and its latch bearing against the removable cross-bar at one end with their opposite ends held by the prongs on the end-strip of the latch to hold the latter in place with its end-strip flat 70 against the end-strip on the slide.

7. In a device of the type specified, the combination of a main link having a top with sides bent downwardly therefrom and folded inwardly to provide lateral bottom-flanges, 75 tabs bent over from the ends of the bottom-flanges, said link having a slotted end portion bent downwardly with its ends held by tabs on the bottom flanges folded thereover, and a slide slidable within the main link and provided with a hook projecting therefrom to engage the slotted end portion of the next adjacent link of the series.

In testimony whereof I affix my signature.
CHARLES H. KESTENMAN.
